(57) **CLAIM**

The ornamental design for sports ball wheel cover, as shown and described.

DESCRIPTION

The pattern of circles on the basketball sports ball wheel cover as shown in the following figures is understood to be repeated uniformly throughout the surface of the wheel cover.

FIG. 1 is an isometric view of a sports ball wheel cover in accordance with an embodiment of the present invention; FIG. 2 is a front view thereof;

FIG. 3 is a left-side view thereof;

FIG. 4 is a right-side view thereof;

FIG. 5 is a top view thereof;

FIG. 6 is a bottom view thereof;

FIG. 7 is a back view thereof; and,

FIG. 8 is a side view of the sports ball wheel cover of FIG. 1, illustrating its mounting position on a wheel drawn in phantom.

The broken line showing of environment is for illustrative purposes only and forms no part of the claimed design.
